UNITED STATES PATENT OFFICE.

ERNEST DAVIS, OF SYRACUSE, NEW YORK, ASSIGNOR TO THE PROSPERITY COMPANY, INC., OF SYRACUSE, NEW YORK, A CORPORATION OF NEW YORK.

EQUALIZING MECHANISM FOR PRESSING MACHINES.

Application filed January 3, 1927. Serial No. 158,492.

This invention relates to pressing machines, particularly laundry pressing machines in which one of the pressing elements as the lower pressing element consists of a plurality of sections or members for ironing at the same time, different portions of a garment as the neck yoke and cuffs of a shirt, and has for its object, a particularly simple and efficient construction and mechanism by which the pressure on said members or sections of the pressing element is distributed or equalized and hence, the pressing or ironing operation made uniform on the parts of a garment, that is, on the neck yoke and the cuffs of a shirt.

The invention consists in the novel features and in the combinations and constructions hereinafter set forth and claimed.

In describing this invention, reference is had to the accompanying drawing in which like characters designate corresponding parts in all the views.

Figure 1 is a fragmentary front elevation of a pressing machine embodying my invention.

Figure 2 is an enlarged fragmentary view of parts seen in Figure 1.

This pressing machine comprises generally, coacting pressing elements, one of which is movable toward and from the other, one of said elements, usually the lower element, consisting of a plurality of members mounted to move relatively to each other when unequal pressure is applied thereto by the other or upper pressing element and means for supporting said members comprising equalizing mechanism for transferring the differential movement of either or any one of said members to the other.

The pressing machine may be of any suitable form, size and construction and as pressing machines of this type are well known, further description is thought to be unnecessary for a complete understanding of this invention.

The machine here illustrated is designed to press the cuffs and the neck yoke of a shirt at the same time, and includes a head 1 and a lower element or buck 2 which is mounted upon a frame 3. The head 1 is carried by any suitable support as a yoke lever 4. This yoke

lever 4 is actuated to raise and lower the head 1 by any well known mechanism. The head 1 is provided with three members or sections 5, 6 and 7 arranged in a row and being concave in general form, and the buck 2 is formed with complementary members 8, 9 and 10, the latter supported on the buck 2 by the equalizing mechanism to be presently described. The coacting members 5, 8 and 7, 10 are shaped to iron the cuffs of a shirt while the coacting members 6, 9 are shaped to press the neck yoke of a shirt.

Spring means are here shown to hold the members 8, 9 and 10 against or to follow the equalizing mechanism or levers. As here illustrated the springs are of the compression type and encircle studs 11 depending from said members 8, 9 and 10 and extending through lugs 12 on the body of buck 2, the springs being interposed between said lugs and nuts or shoulders 13 on the studs.

The equalizing mechanism comprises levers 14, 15 between the members 8, 9 and the members 9, 10 respectively. Each of the levers are fulcrumed between its ends at 16 and has its ends extended upward and pressed against the lower sides of the members 8, 9 and 10. The outer end of the lever 14 presses against the member 8 and the outer end of the lever 15 against the member 10, and the inner ends of both levers press against the lower side of the intermediate member 9 near the center thereof. The fulcrums 16 are here shown as screw bolts adjustable to move the levers so that their ends normally engage both members 8, 9, or 9, 10.

The members 8, 9 and 10 are usually provided with suitable pads 17 and these pads may be of any suitable form, size and construction and are usually spring pads although they may be ordinary fibrous padding material. The form of the padding forms no part of this invention.

In operation, the work, as a shirt, is placed on the lower pressing element when the head 1 is up, the neck yoke being placed on the member 9 and the cuffs on the members 8 and 10, the head is then brought down onto the buck under pressure. If the machine is nicely adjusted, the pressure will be uniform even if the neck yoke is not as thick as the

cuffs, without action on the part of the equalizing levers. If however, for any reason, the pressure is unequal or for instance, if the pressure is greater on the cuff supporting members 8, 9 than on the intermediate member 10, the differential movement will be transferred through the levers 14, 15 to the intermediate member 10 and press the same upward. Also, if the heaviest pressure is on the intermediate member, the intermediate member will be depressed and force upward the cuff supporting members 8, 9 and thus equalize the pressure. It is generally the case that the cuff supporting members are more liable to normally receive more pressure than the intermediate neck yoke supporting member 9, and the equalizing mechanism is primarily intended to boost the pressure on the intermediate member.

20 In machines of this type heretofore used, the neck yoke is oftentimes not satisfactorily pressed or ironed because of the pressure being greater on the cuff ironing members than on the intermediate yoke pressing member.

25 By my invention, all the parts receive equal pressure owing to the equalizing mechanism between the members 8, 9 and 10.

What I claim is:

1. A pressing machine comprising coacting pressing elements, one movable toward and from the other, one of said elements comprising a plurality of members movable relatively to each other when unequal pressure is applied thereto by the other pressing element and equalizing mechanism to support said members and transfer the differential movement of either member to the other.

2. A pressing machine comprising coacting pressing elements, one movable toward and from the other, one of said elements comprising a plurality of members movable relatively to each other when unequal pressure is applied thereto by the other pressing element, means for supporting said members including equalizing mechanism for transferring the differential movement of either member to the other.

3. A pressing machine comprising coacting pressing elements, one movable toward and from the other, one of said elements comprising a plurality of members movable relatively to each other when unequal pressure is applied thereto by the other pressing element, means for supporting said members comprising an equalizing lever fulcrumed between its ends and bearing at its opposite ends against said members.

4. A pressing machine comprising coacting pressing elements, one movable toward and from the other, one of said elements comprising a plurality of members movable relatively to each other when unequal pressure is applied thereto by the other pressing element, mechanism for transferring the differential movement of either member to the other, and

spring means holding said members against said mechanism.

5. A pressing machine comprising coacting pressing elements, one movable toward and from the other, one of said elements comprising a plurality of members movable relatively to each other when unequal pressure is applied thereto by the other pressing element, an equalizing lever between said members for transferring the relative movement of either support to the other, and spring means for holding the said members against the levers.

6. A pressing machine comprising coacting pressing elements, one movable toward and from the other, one of said elements comprising three members movable relatively to each other when unequal pressure is applied thereto by the other pressing element, means for supporting said members and transferring the differential movement of any one of said members to the others.

7. A pressing machine comprising coacting pressing elements, one movable toward and from the other, one of said elements comprising three members arranged in a row and movable relatively to each other when unequal pressure is applied thereto by the other pressing element and mechanism for transferring the differential movement of the two end members to the intermediate member and of the intermediate member to the end members.

8. A pressing machine comprising coacting pressing elements, one movable toward and from the other, one of said elements comprising three members arranged in a row and movable relatively to each other when unequal pressure is applied thereto by the other pressing element and mechanism for transferring the differential movement of the two end members to the intermediate member and of the intermediate member to either or both of the end members, said mechanism comprising equalizing levers, each fulcrumed between its ends and at its opposite ends bearing on one of the end members and the intermediate member.

9. A pressing machine comprising coacting pressing elements, one movable toward and from the other, one of said elements comprising three members arranged in a row and movable relatively to each other when unequal pressure is applied thereto by the other pressing element and mechanism for transferring the differential movement of the two end members to the intermediate member and of the intermediate member to either or both of the end members, said mechanism comprising equalizing levers each fulcrumed between its ends and at its opposite ends bearing on one of the end members and the intermediate member, said levers thrusting against the intermediate member near the center thereof.

10. A pressing machine comprising coacting pressing elements, one movable toward and from the other, one of said elements comprising a plurality of members movable relatively to each other when unequal pressure is applied thereto by the other pressing element and mechanism for transferring the differ-

ential movement of either member to the other.

In testimony whereof, I have hereunto signed my name, at Syracuse, in the county of Onondaga, and in the State of New York, this 20th day of November, 1926.

ERNEST DAVIS.
